UNITED STATES PATENT OFFICE.

JOSEPH K. DAVISON, OF PHILADELPHIA, PENNSYLVANIA.

DESIGN FOR A BADGE.

SPECIFICATION forming part of Design No. 18,729, dated November 13, 1888.

Application filed August 7, 1888. Serial No. 292,162. Term of patent 14 years.

To all whom it may concern:

Be it known that I, JOSEPH K. DAVISON, a citizen of the United States, residing in the city and county of Philadelphia, State of Pennsylvania, have invented and produced a new and original Design for a Badge, of which the following is specification, reference being had to the accompanying photograph, forming part thereof.

10 The leading feature of my design for a badge is a bar with the representation of a grasshopper thereon.

In the accompanying photograph, to which reference is made, 1 represents a sunflower, 15 which is at the bottom of the ribbon 2, and 3 represents a bar at the top thereof. On the bar, which has a curved top, angular corners,

and a scroll at bottom, is a representation of a grasshopper walking in a field of grain.

I claim—

1. A design for a badge, consisting of the representation of a sunflower, the ribbon, and a bar with the representation of a grasshopper, substantially as shown and described.

2. In a design for a badge, a bar having a 25 curved top, angular sides, and a scroll at the bottom, and having on its face the representation of a grasshopper in a field of grain, as shown and described.

JOS. K. DAVISON.
